EYEGLASS CASE

Emanuel Nathan, South Orange, N. J.

Application June 20, 1951, Serial No. 15,611

Term of patent 14 years

(Cl. D57—1)

To all whom it may concern:

Be it known that I, Emanuel Nathan, a citizen of the United States, residing at South Orange, in the county of Essex and State of New Jersey, have invented a new, original, and ornamental Design for an Eyeglass Case, of which the following is a specification, reference being had to the accompanying drawing, forming a part thereof.

In the drawing:

Fig. 1 is a front perspective view of an eyeglass case, showing my new design, the opposite side presenting substantially the same appearance as the side shown; and

Fig. 2 is a front elevational view on an enlarged scale of the engaging means and a fragment of the eyeglass case frame.

I claim:

The ornamental design for an eyeglass case, as shown and described.

EMANUEL NATHAN.
